(57) **CLAIM**

The ornamental design for a gaming table, as shown and described.

DESCRIPTION

FIG. 1 is a top angled perspective view of a gaming table according to an embodiment of the present disclosure;

FIG. 2 is a front side view thereof;

FIG. 3 is a back side view thereof;

FIG. 4 is a right side view thereof;

FIG. 5 is a left side view thereof;

FIG. 6 is a top view thereof;

FIG. 7 is a bottom view thereof;

FIG. 8 is a top angled perspective view of a second embodiment of the present disclosure;

FIG. 9 is a front side view thereof;

FIG. 10 is a back side view thereof;

FIG. 11 is a right side view thereof;

FIG. 12 is a left side view thereof;

FIG. 13 is a top view thereof; and,

FIG. 14 is a bottom view thereof.

The broken lines depict unclaimed environmental subject matter.
